(57) **CLAIM**

The ornamental design for a blanking panel, as shown and described.

DESCRIPTION

FIG. 1 is a perspective view of the blanking panel of the invention;

FIG. 2 is a front elevation view of the blanking panel of FIG. 1;

FIG. 3 is a bottom plan view of the blanking panel of FIG. 1, the top being a mirror image; and,

FIG. 4 is an elevation view of an end of the blanking panel of FIG. 1.

The rear forms no part of the claimed design. The broken lines are intended to show environmental structure and form no part of the claimed design.
